(Cl. D92—26)

To all whom it may concern:

Be it known that I, John J. Maibach, a citizen
of the United States, residing at New York city,
county of New York, and State of New York, have
invented a new, original, and ornamental Design
for a Tablecloth, of which the following is a speci-
fication, reference being had to the accompany
drawing, forming part thereof.

The figure is a plan view of a tablecloth, show-
ing my new design.

I claim:

The ornamental design for a tablecloth, sub-
stantially as shown.

JOHN J. MAIBACH.
